UNITED STATES PATENT OFFICE.

GEORGE A. MATTERN, OF BERKELEY, CALIFORNIA.

BATHING SUIT.

1,421,704.

Specification of Letters Patent.

Patented July 4, 1922.

Application filed August 2, 1921. Serial No. 490,467.

To all whom it may concern:

Be it known that I, GEORGE A. MATTERN, a citizen of the United States, residing at Berkeley, in the county of Alameda and State of California, have invented certain new and useful Improvements in Bathing Suits, of which the following is a specification.

My invention relates to the class of bathing-suits. These garments are usually made of knitted goods; and comprise a trunk portion and a leg portion, to which, is added a skirt portion.

Knitted fabric is relatively elastic in one direction and non-elastic in a direction at right angles to its elastic phase.

Bathing-suits should fit the wearer closely and to this end they are made with the elastic phase of the goods running circumferentially of the garment, that is horizontally around the wearer, the non-elastic phase running vertically. As the length of the garment must also be as closely as possible proportionate to the wearer, it follows that in securing the circumferential close fit, the initial length fit is, under the stretching of the elastic phase, even more closely shortened; and as, in this direction, the goods are relatively non-elastic, the result is an inconvenient lengthwise tightening of the garment on the wearer, giving undue pressure on shoulders and crotch.

The object of my invention is to overcome this difficulty; and to this end my invention consists in the novel bathing-suit which I shall now fully describe by reference to the accompanying drawings, in which—

Fig. 1 is a front view of my bathing-suit.

Fig. 2 is a rear view of the same.

Fig. 3 is a rear view of the suit turned inside out.

Fig. 4 is a vertical section, enlarged, on the line 4—4 of Fig. 1, through both front and back, the dotted lines showing the position under the yielding of the insert member 4.

The bathing-suit is made of knitted goods and comprises a trunk portion 1, a leg portion 2, and a skirt portion 3.

In all these portions the elastic phase of the goods runs circumferentially, as is indicated by the vertical shading and the horizontal arrows in the several figures. In the

front of the garment, this phase of the goods is as usual continuous and unbroken from end to end of the garment, as shown in Fig. 55 1; but in the back of the garment, as shown in Fig. 3, this is not the case, for between the base of the trunk portion and the top of the leg portion, there is inserted a strip 4 of suitable material, having an elastic phase in one 60 direction only, which direction is up and down of the garment, that is, at right angles to the elastic phase of portions which it joins. This is indicated by the horizontal shading in Fig. 3 and by the vertical arrows 65 in Figs. 3 and 4. This strip is only in the back of the garment and extends approximately the width thereof. In its best and preferred form this insert member 4 is of knitted goods.

In the skirted suit herein illustrated, the strip 4 lies under and is concealed by the skirt. Fig. 2.

It will now be seen that the suit may be made a close fit both circumferentially and 75 lengthwise, and yet give relief from the relatively non-elastic vertical pressure, by reason of the insert member 4, the elastic phase of which is up and down.

I claim:

1. A bathing-suit of knitted goods comprising a trunk portion, a leg portion, and a skirt portion, in all of which the elastic phase of the goods is circumferential; and a strip inserted in and extending across the 85 width of the back only of the garment under the skirt portion and between the base of the trunk and the top of the leg portion, said strip having an elastic phase at right angles to the elastic phase of said portions. 90

2. A bathing-suit of knitted goods comprising a trunk portion, a leg portion, and a skirt portion, in all of which the elastic phase of the goods is circumferential; and a strip of knitted goods inserted in and extending across the width of the back only of the garment under the skirt portion and between the base of the trunk and the top of the leg portions, said strip having its elastic phase at right angles to the elastic phase of 100 said portions.

In testimony whereof I have signed my name to this specification.

GEORGE A. MATTERN.
